2,403,766

MEANS FOR THE PRODUCTION OF
KNITTINGHerbert Noel Smith and Elizabeth Ethel Smith,
Daventry, EnglandApplication June 13, 1942, Serial No. 446,912
In Great Britain May 10, 1941

61 Claims. (Cl. 66—1)

1

The present invention relates to improvements in knitting machines.

We have described in our prior Patent application Serial No. 351,622, filed August 6, 1940, now Patent No. 2,353,197, a new method and form of machine in which the usual beard and latch needles are not employed, the new method of knitting being to engage the yarn and form the new loop through an already formed stitch whilst this is held open and guarded from the looping or stitch-forming means.

In accordance with the present invention the machine comprises a looping or stitch-forming means constructed and arranged to engage the thread and form a new loop through a previously formed stitch while this is held open around a guard member, such means so co-operating successively with a series of such members and the stitches thereabout. The machine is preferably so constructed and arranged to operate that the looping means can form a loop selectively in either direction through a previously formed stitch.

We would have it understood that we make no claim to machines in which the thread is carried through the previously formed stitches by a needle having a permanently closed eye through which the thread is threaded and we regard it as essential that the stitch-forming means should be so constructed and arranged as to form each of successive stitches by first engaging the thread and then carrying the loop of the new stitch through the old stitch while the latter is about its guard.

The guard members and a stitch former or formers may be relatively displaceable so that the or each stitch-former co-operates with successive members, e. g., the members may travel towards the stitch-former or formers, or the stitch former or formers may travel from one member to another.

The guard members are preferably channelled where the stitch is held as this greatly contributes to ensuring that the thread-engaging portion of the stitch-former and this is preferably an open hook, shall pass safely through the old stitch without catching the thread thereof and preferably the hook is directed towards the bottom of the channel. Other forms of guard which will hold open the stitch through which the stitch former is to pass will serve, such as a slotted form, or a flat blade or the like will serve if the stitch thereabout is suitably held and tensioned but the channel or like forms are preferred by which the stitch is kept open without relying up-

2

on pull on the stitch in a predetermined direction.

The new loop is preferably accepted by a different member from the guard member carrying the stitch through which it was formed, although it may be accepted by such guard member.

We may provide a series of guard members and a series of accepting members moving progressively towards a stitch former, the guard members coming successively with a previously formed stitch into knitting relation with the stitch former and the accepting members successively moving forward to accept a new loop. According to other forms of the invention the stitch former or formers travel and co-operate successively with different guard and accepting members.

The guard and accepting members may each be constructed and arranged to serve at one time in the cycle of operations as a guard and at another time as an accepting member. This is advantageous, e. g., where as will be hereinafter described, travelling stitch conveying members are used and there are two knitting stations, or where the flow of knitting is periodically reversed, or where the conveying members travel as a single endless series. In other forms of the invention, e. g., where there are two separate series of travelling conveying members and one knitting station and one station where the stitches are transferred from one series back to the other, one series of such members may serve only as guards and the other series only as accepting members.

The machine is preferably adapted to knit plain and purl stitches selectively and it may be adapted to knit in reverse directions for flat knitting or continuously in one direction for tubular or circular knitting and in some cases the same machine may be arranged to knit flat or tubular fabric. Where the machine is required to knit flat only the conveying members may merely travel to and fro. When it is to knit tubular or circular fabric the continuous travel of the conveying members may be achieved by an endless system or systems of such members. For example there may be one endless series and the stitch-forming member constructed and arranged to co-operate successively for knitting with two of such members which are separated from each other by others of the series, e. g., the endless system may comprise two parallel reaches and the stitch former arranged to knit across from one reach to the other. Alternatively there may be two endless systems and each new stitch carried through a stitch on a member of one system and accepted by a member of the other series.

The travel of the endless systems may be periodically reversed for flat knitting.

The stitch-forming member may be arranged to work between co-operating upright guard and accepting members, e. g., by arranging the latter so that the channel of the guard member which is for the time being operative faces the channel in the member which is to accept the new stitch.

The casting off of the stitch on the guard member may be facilitated by causing the guard to recede out of the stitch, e. g., by a sliding or rocking motion, and the accepting member may receive a movement into the new loop, e. g., may be mounted to slide or rock, or, alternatively, the stitch-former may be so constructed and arranged to operate as to cast off the old stitch from the guard and/or deposit the new stitch on the accepting member without the aid of any such movement of recession and entry of the guard and accepting members.

Preferably the machine will have two knitting stations, and the knitting stations may in some forms be movable to vary the number of conveying members effective for knitting. More than two may be provided by appropriately varying the course of the conveying members, each dealing successively with stitches which are awaiting a new loop.

The conveying members may be constructed and arranged to form internal gear teeth which engage for drive with toothed driving wheels and thrust one another along the course. Alternatively they may be carried by an endless conveyor, e. g., a chain conveyor, or by two such conveyors where necessary.

The stitch former may comprise a curved arm connected to a medial axle or bearing about which such arm oscillates. This oscillatory motion is very convenient for first engaging the thread and then drawing the loop and it may also assist in landing the new loop and in subsequently permitting the stitch-former to disengage itself from the loop.

The stitch-former (looper) axis may be displaceable, especially when the looper is required to cast off the old stitch and/or to deposit the new loop and this axis may be movable up and down once to enable the new loop to be formed and the old stitch to be cast off and again to enable the new stitch to be landed and released from the looper and a further displacement of the looper axis across the machine may be provided for the purpose of taking the new loop to the accepting part.

The direction in which the oscillatable looper enters the old stitch may be controlled by cams which are interchangeable automatically under the control of Jacquard or other stitch determining mechanism. The looper may be given an initial angular displacement about its axis of oscillation in either direction so as to relate it for knitting in either direction of flow of the knitting and similarly controlled interchangeable cams may be provided for this purpose. Four interchangeable cams may be used so that the looper can draw the new loop selectively in either direction through the old stitch in either direction of flow of knitting. The direction in which the looper axis is taken across the machine may also be reversible in accordance with the direction of flow of the knitting by means of cams which are interchangeable. The movement of the conveying members, or of the looper when this travels,

may be under the control of interchangeable intermittent mechanisms.

The thread layer also may be under the Jacquard or other stitch-determining control so as to be capable of co-operating with the looper for knitting either plain or purl stitches in whichever direction the knitting is progressing.

In certain forms of the invention the guard member may be displaceable to elongate the new loop while the latter is held by the looper, the accepting member accepting the new loop while it is held elongated and particularly in this form it is advantageous to move the guard members progressively step-by-step inwards as they approach the knitting station and the accepting members outwards as they recede from the knitting station. The guard members preferably rock away from the stitch former in elongating the loop and slide transversely in receding out of the old stitch when the new loop has been accepted. The accepting member also preferably slides transversely inwards in order to pass through the new loop. The guard members may in this form each have a guard channel or slot which opens upwards and the looper arranged to oscillate about a fixed axis thereabove and the accepting members may be given a chisel shaped edge chamfered to a point which is arranged to move in close juxtaposition to the hook in penetrating the new loop supported by the hook.

These last features are hereinafter illustrated by way of example in a form of apparatus in which there are two endless systems of conveying members each system being in the form of spaced-chain conveyors having transverse guides for the guard and accepting members and in another form in which the looper travels in lieu of the guard and accepting members.

In order that the invention may be the more readily understood reference is hereinafter made to the accompanying drawings which illustrate various forms of construction.

Fig. 1 is a front elevation of one of such forms, Fig. 2 being an end elevation in the direction of the arrow 2 of Fig. 1. Fig. 3 is a view from the same direction but with the end bracket C Fig. 2 removed and showing only the lower part of the machine. Fig. 4 is a sectional end elevation looking in the direction of arrow 4, Fig. 1, and Fig. 5 is a detailed front elevation on the line 5—5 of Fig. 4 of the looper mechanism. Figs. 6, 7 and 8 are end, front and back elevations of one of the conveying members and Fig. 9 is a fragmentary detailed view showing the way these members are driven by the sprockets. Figs. 9a to 9k show various positions of the parts while the looper is forming a new loop and landing it on the accepting member and releasing the old loop from the guard member and Fig. 9l shows diagrammatically in plan the introduction of a second knitting station instead of causing the loops to travel round one end of the system as in Fig. 9b.

Fig. 10 is a half front elevation of a modified form of the machine, Fig. 11 is a half plan view of this machine, Fig. 12 is a part longitudinal sectional view, Fig. 13 is a part end sectional view and Fig. 14 a part end sectional view showing certain parts of the looper mechanism. Fig. 15 is an end view of Fig. 14 showing one of the cams therein illustrated whilst Fig. 16 is a fragmentary end view looking at the looper. Figs. 17, 18 and 19 are face views of the other three cams shown in Fig. 14. Fig. 20 is another fragmentary end view looking at the looper. Fig. 21 is another fragmentary longitudinal view of the cams shown

in Fig. 14 and Figs. 15-19. Fig. 22 is a longitudinal sectional elevation of the thread layer mechanism, Fig. 23 is an end view of such mechanism, partly in section and Fig. 24 a plan view thereof. Figs. 24a to 24f show how by this modified apparatus a loop may at any time be formed automatically in the reverse direction through an old stitch, employing the other looper hook to the one operation in Figs. 9a, etc.

Figs. 25-34 show diagrammatically a further modified form of machine in which the conveying members are carried by two endless conveyors and the looper knits from the members on one conveyor to those on the other, Fig. 25 being a longitudinal elevation thereof, Fig. 26 an end sectional elevation and Fig. 27 a further end sectional elevation. Fig. 28 is a detail view showing the loop formation and Fig. 29 a plan of one knitting end. Fig. 30 is another plan of the means for displacing the guard members progressively inwards and the accepting members progressively outwards to and from the knitting station. Fig. 31 is a plan view of a part of one of the chains of the conveyors and Fig. 32 is a front view thereof. Fig. 33 is a longitudinal elevation and Fig. 34 an end view of one of the guide members which bridge the two chains of a conveyor and serve to receive the conveying members.

Figs. 35 to 40 show diagrammatically a further form of machine with two endless systems, Figs. 35 to 37 showing fragmentarily the way the looper co-operates with the conveying members for the time being at the knitting station and Figs. 38 and 39 the way the conveying members are related for displacement by the sprockets, Fig. 40 being a detail view of the channelled portion of one of the conveying members.

Fig. 41 is a diagrammatic end elevation showing a variant form of machine in which the looper travels in lieu of the guard and accepting members; Figs. 42 and 43 are detail views of the looper and thread-layer of this machine and Figs. 44 and 45 are detail views of a means for reversing the looper carriage.

Figs. 46 to 48 show how the operation of the machine shown in Fig. 41 may be modified so that the loops are accepted by the same guard members as carried the stitches through which they were formed.

In the form of machine illustrated in Figs. 1-9, the stitch guard members are constituted by stitch-conveying members 1 and are in the form of a series of uprights each having a channelled guard portion 2 and being pointed at 3. They are arranged side-by-side as an endless series and are advanced intermittently along an endless track 4.

A convenient method of moving the conveying members round the endless track is to provide at each end of the endless system two co-axial sprocket wheels 5, 6 at different levels and locally to shape the conveying members at 7, 8 (see Figs. 6-9) so that the series of members passing round the curved ends of the system form what are in effect internally toothed gears co-operating with the sprockets.

The upright members of one reach of the endless system are situated with their longitudinal channels facing the channels of the members of the opposite reach. In combination with such members we use a stitch-forming means or looper 9 which passes directly through the channel of each member (and the stitch thereabout) as the members are brought successively into knitting position and the new stitch is accepted by one of

the members of the opposite reach as such members are brought forward successively.

The looper is fast with an oscillatable spindle 10 which is arranged parallel to the two opposite reaches of the system of conveying members and this spindle is movable up and down and to fro across the machine.

The looper may take the form of a part circular, e. g., C-shaped, member the two ends 11, 12 of such member being hooked outwards, the hook for the time being in operation moving through the guard portion of the conveying member and through the old stitch thereabout to engage the thread and moving back through the guard to draw the new loop through the old stitch and thence across the machine to carry this loop onto the accepting point of a conveying member of the opposite reach. The old stitch is cast off the guard member by the looper as it draws over the new loop and another guard member moves forward. That accepting member which has taken the previously formed new stitch is moved on and by the time the new loop has been brought across the endless system the next accepting member has moved forward to accept the new loop. The looper then returns across the machine. The looper not only rocks about its axis for engaging the thread and carrying the new loop through the old stitch, but it moves upwards for drawing the new loop and drawing off the old stitch from the guard and across the machine and downwards for depositing the new stitch on the accepting point.

The looper spindle 10 has a bevel wheel 13 which meshes with a bevel wheel 14 at right angles to it on a vertical shaft or spindle 15 carrying a helical gear 16 driven by a helical gear 17 for oscillating spindle 10. The bearing 18 for the looper spindle 10 has upstanding rods 18a which are vertically slidable in a slide block 19 which is movable across the machine guided by fixed rod 19a and by a rod 20 which moves with the block and is slidable in the frame 21.

The slide block 19 is normally urged in one direction across the machine by a helical spring 22 and is moved in the reverse direction across the machine against this spring by a lever 23 pivoted on the machine frame at 24 and rocked by a follower 25 of a cam 26 on a vertically slidable bar 27.

The main shaft 28 of the machine is arranged to be rotated and it carries the large spur wheel 29 which gears with a spur wheel 30 on the long shaft 31 and a spur wheel 32 on a second long shaft 33. On these shafts 31 and 33 are eccentrics 34, 35 which operate sleeves 36, 37, the former being connected by rods 38 to the vertically guided cam bar 27 and the latter through rods 39 to the vertically guided cam bar 40 so that the bars are given a vertical reciprocating motion by the eccentrics. The bar 40 carries a pin 41 which rocks in a slot 42 in a lever 43 pivoted at 44 to the machine frame and arranged at its free end 45 to engage and rock a cam having two cam surfaces 46, 46a and mounted on a shaft 47 carrying a large bevel wheel 48 engaging a bevel wheel 49 on shaft 50 which mounts the helical gear 17. The gear 17 is slidable along a key-way 51 in shaft 50. The spindle 15 is slidable with reference to helical wheel 16 by a key-way connection 51a, the wheel 16 being axially fixed. On the shaft 47 carrying the large bevel wheel, there is a cam 52 which depresses a slide 53, which is guided by the rods 54 in a fixed part of the frame, against a spring

55 so that upon the upward swing of the cam-engaging end of the lever 43 it engages cam surface 46 and rocks the shaft 47 in one direction, the spring reversing the lever when it becomes free of cam 46, and on the downward motion of that end of said lever it engages cam surface 46a and is again rocked in the same direction and subsequently returned by spring 55, so that during each part turn of the main shaft the large bevel wheel 49 is given two oscillations and through the intermediate mechanism between such wheel and the looper spindle, the latter is also given two oscillations for each part turn of the main shaft, so that the looper first turns in one direction to pass through the old stitch on the guard and engage the thread and then returns through the old stitch with the thread to draw the new loop and then when the slide block 19 has moved towards the other side of the machine, the looper receives a second oscillatory motion in order to land and disengage itself from the new loop on the accepting point. In order that the looper shall rise to cast off the old stitch and move down to land the new loop the bearing 18 carrying the looper spindle is given an up and down motion by the following means. The shaft 33 carries a spur wheel 56 which gears at the rate of 2:1 with a second gear 57 on a stub shaft 58 on the machine frame which shaft 58 carries an eccentric 59 which, through the eccentric sleeve 60, imparts a reciprocatory motion to a rod 61 pivoted to rod 62 which is pivoted at 63 to the machine frame and whose other end has a lateral extension 64 which engages with a forked portion 65 of the slide block 18a and through such gearing the bearing for the looper spindle is thus raised and lowered twice for each turn of the main shaft. The cam bar 27 operated from the eccentric 34 on the spindle 31 has its cam portion 26 arranged to force outwards the slidable follower 25 during its upward motion and this follower rocks the lever 23 which presses on the rod 20 projecting from the slide block 19 in order to force the slide block across the machine against the action of the spring 22. The slide block makes one to and fro motion across the machine with each turn of the main shaft.

Co-operating with the looper is a thread layer 66 for laying the thread across the path of the looper hook. The boss 73 of the thread layer is mounted sufficiently freely upon the fixed rod 67 of the machine frame that it can rock longitudinally of the machine. For this purpose the slide bar 40 is provided with a cam 68 which engages with one end of a rod 69 which is guided in the machine frame and which at the other end is arranged to rock a lever arm 70 on the spindle 71 carrying a second lever arm 72 which engages with the outer part of boss 73 (Fig. 4). The boss is held against rotation on the rod 67 by pin 73a. The boss is raked away outwards from the point where it bears on a collar 67a (see Fig. 1) on the rod 67 so that its outer end can be rocked towards the collar by lever 72. This rocking of the lever-like threadlayer longitudinally of the machine is against the pressure of a helical compression spring 74 which is housed in a hole in the collar 67a and presses on the boss 73 in opposition to the end of lever 72 and returns the thread layer when the cam 68 on the bar 40 is withdrawn. The laying end of the threadlayer thus receives an arcuate movement sufficient to lay the thread satisfactorily.

In order that the looper shall pass behind the

connecting piece of thread (see 75a in the diagram, Figs. 9b and 9d, hereinafter referred to) which comes from the thread supply and lies across the machine between the guard member 5 and the accepting member during the loop formation, the thread is pressed away from the knitting station by a depresser blade 75 pivoted to the machine frame at 76 and arranged to be rocked periodically against the force of a spring 77 through the medium of a wire or tension member 18 connected to a lever 79 having a cam surface 80 which is operated by the upper end of the vertical slide bar 27 to rock the lever and thereby the depresser once for each turn of the main shaft. A fixed member 81 may be provided for holding down the fabric adjacent the guard and accepting members to ensure that only that loop through which the stitch has just been formed is carried off the guard by the looper, and that the threads not lifted off the accepting member when the looper is in a raised position and is transferred to the accepting side of the system.

There is a second eccentric 82 on the shaft 31, the sleeve 83 of which is connected to a rod 84 pivoted to a lever arm 85 on a spindle 86 carrying a second lever arm 87 which is forked to engage between collars 88 on an axially slidable shaft 89 which is fast with a second parallel slidable shaft 90 having a fixed arm 91 pivoted to a pawl 92 so that as the shaft and arm 90, 91 reciprocate an oscillatory motion is imparted to the pawl and with each go and return stroke of the slidable shaft a ratchet 93 is racked round by the pawl one tooth. The pawl is urged into contact with the ratchet by spring 94. The ratchet is on shaft 95 carrying the sprocket wheels 5, 6, which drive the conveying members. The arm 91, and the ratchet and pawl system is duplicated at the other end of the machine so that both ratchets can derive their movement from the reciprocation of the shaft 90.

The new stitch deposited on the accepting member is carried round the system back to the knitting station and a new stitch is knitted through it, but it is usually desirable not to convey the stitches round the sprockets and they may be merely transferred from one reach to the other, but there will preferably be a second knitting station. Thus a tubular length of fabric can be knitted. The looper need have only one hook, or as shown, it may have two hooks and the machine modified, as will be hereinafter described, for reversing the direction in which the looper is drawn through the guard so that plain and purl stitches may be produced. Furthermore the modified machine as now to be described may be arranged to reverse the flow of the knitting so that flat fabric can be knitted. It will be understood that although the simple form of the machine may have only one knitting station there will as before described, preferably be more than one such station, e. g., the looping and thread-laying mechanism may be duplicated at the other end of the system and so arranged that the looping mechanism knits across the machine in the opposite direction to the looping mechanism described.

The method of knitting on the present machine will be more clearly understood from the illustrations Figs. 9a to 9k. It will be borne in mind that the slide 19 in which the looper is oscillatably mounted moves once across the machine and back and at the same time has two up and down movements, one up and down movement on one side of the machine to take the

looper down into co-operation with the guard and back and another on the opposite side of the machine to take the looper down on the outside of the accepting member to land the new loop and back. The looper is oscillated once when it is about at its lowermost position on the one side of the machine to form the new loop and again to detach the loop when it is about at its lowermost position on the opposite side of the machine.

Fig. 9a shows the looper in dotted outline in its raised position when the spring 22 is forcing the slide to the right at a speed determined by cam 26 and its operating eccentric 34, and simultaneously the operation of eccentric 59, rod 61 and lever 62 lowers the slide, so carrying down the looper towards the right in the general direction of arrow A. The depresser 75 has meantime been operated by bar 27 turning lever 79, to move the thread 75a lying between the thread layer and the last new loop and the fabric adjacent the old stitch X clear of said stitch. The full line position (Fig. 9a) of the looper shows the looper ready to be turned through said old stitch X about the channelled part of member 1a, the fabric being omitted for clarity. Fig. 9b shows the thread and fabric moved by the depresser 75. In moving down to this position the looper has merely suffered a bodily displacement. Now the bar 40, which is on its rising stroke by the action of eccentric 35, through the tip 45 of lever 42 engages cam 46 and rocks shaft 47 which through the large ratio gear 48, 49 imparts a rapid turn to the looper to the position shown in Fig. 9c. The laying end of the threadlayer 65 is shifted along the machine by cam 68 on bar 40 operating rod 69, thus laying the thread across the stem of the looper (see Fig. 9d). The tip 45 of the lever 42 will now have moved up and spring 55 now quickly returns the shaft 47 and cam 46 to normal position so that the gearing 48, 49 turns back and the looper hook also moves sharply back to take the thread, as the new loop Y, through the stitch about the guard, see Fig. 9e. During these rapid movements of the looper about its axis of oscillation little bodily movement has occurred, the cam 26 and eccentric 34, which is now moving on the arc which produces little or no travel, controlling the rate of movement across the machine and eccentric 59 the rate of simultaneous up and down movement of the slide 19. The eccentric 34 now carries bar carrying cam 26 in the reverse direction causing the said cam to rock lever 23 in the reverse direction, i. e., to carry slide 19 back towards the left and eccentric 59 through rod 61 and lever 62 now lifts the slide at the same time, that is the looper is moved in the opposite direction to arrow A. Figs. 9f and 9g show the new loop of Y being drawn to the left and upwards and initiating the drawing off from the guard of old stitch X, the adjacent guarded loops being prevented from being inadvertently also lifted off their guard members by member 81 which is merely a fixed platelike member which stops the said loops from rising. Figs. 9h and 9i show the up movement to the left continued and the old loop X completely drawn off guard 1a and depresser 75 retracted. When the slide is approximately half-way on its travel towards the left the eccentric 59 will have made one rotation (it will be recalled that by its two to one drive before referred to it makes two rotations to one of eccentric 34 and it now starts the rod 61 and lever 62 moving in the reverse direction again to carry down the slide 19 while it continues its movement to

the left until (see Fig. 9j) the new loop is landed on an empty member 1b. After this has been done the eccentric 59, through movement of bar 40, will have brought the tip 45 of lever 42 into engagement with cam surface 46 again to rock shaft 47 to turn the looper in the direction to free it from the landed loop (Fig. 9k) and, the looper now starting its return bodily upward movement towards the right, the second oscillation of the looper is completed so that the looper clears the landed loop and moves back to starting position showing in Fig. 9a.

It will be observed, see Fig. 9b, that the series of members 1 to the left of that figure from the knitting position will be carrying old stitches, and after old stitch X has been lifted off member 1a and new loop Y deposited on member 1b, the endless system of members operated through the train of mechanism from eccentric 82 to the ratchet 93 on the shaft of sprockets 5 and 6, is turned one step thus carrying the empty member 1a to the right to form one of a series of reserve members extending round the right hand end of the endless system and replacing such member by a new stitch carrying member, while the member 1b which has accepted the new loop moves to the left and is replaced by another member from the reserve supply. Another looping operation then commences. Eventually the member 1b will be brought round in its turn to the position occupied by member 1a in the previously described operations, so that the loop Y, as a new stitch will in turn be penetrated by the looper and a new loop formed through it.

Fig. 9l shows the alternative method previously referred to of employing two knitting stations, when there will be a reserve supply of empty members at each end of the system depending on the width of the fabric being knitted, the one looper 9 at the right working from one reach to the other and the second looper 9 at the left working in the opposite direction from the second reach back to the first, so that one looper carries the new loops across the machine in one direction and the other carries new loops across the machine in the reverse direction, and like the form shown in Fig. 9b, a tubular fabric results.

Figs. 9a to 9l show how the fabric bridges the machine at the looping station, or at each looping station, and how it hangs down between the opposite reaches, and where there is only one knitting station, how it extends round one end of the endless system.

In the modified form of the machine shown in Figs. 10 to 24, the conveying members are arranged as before described in an endless track and are driven by toothed wheels or sprockets at each end of the track for progressively advancing the conveying members around said track, but the sprocket shafts are driven by worm and worm devices 96, 97, the worms being on shaft 157.

The looper as before is arranged on spindle 10 which rotates in bearing 18, the spindle 10 having bevel wheel 13 gearing with bevel wheel 14 on the lower end of spindle 15 which carries helical gear 16 meshing with helical gear 17. This gear is, in the form now referred to, on a shaft 98 which carries a bevel gear 99 meshing with another such gear 100 on shaft 101.

On the shaft 101 is a pinion 102 (Fig. 11) meshing with a rack 103 which is arranged to be moved up and down by cams 104, 105, 106, 107 (Figs. 14-18) selectively as will hereinafter be described, the spring 108 (Fig. 14) effecting the

return motion. The lower end of the rack 103 carries a roller 109 which is shown in Fig. 14 engaging the cam 107. The cams are carried by shaft 110 which corresponds to the long shaft 33 in the former machine and is driven from the main shaft 43a by gearing 120, 121 so that it has two revolutions to each turn of the main shaft, each turn of the cam oscillating the looper twice.

The bearing 18 is on a slide 111 (Figs. 12 and 14) which has an upwardly extending rack 112 which meshes with a gear 113 on shaft 114 which is driven by bevel gearing 115, 116 (Figs. 11 and 13), the shaft 117 having gear 118 (and see Fig. 20) which is engaged by a rack 119. The rack 119 derives its motion from the main shaft 43a of the machine by the following mechanism. The shaft 43a carries a gear 120 (see Fig. 13) driving the gears 121, 122 on shafts 110 and 129, the shaft 110 being geared at 121, 124 to a shaft 125 carrying an eccentric 126 which operates the eccentric strap 127 which is pivoted at 128 to the rack 119 and thus reciprocates the rack. The gearing is such that shaft 125 receives two rotations to one rotation of shaft 110. In this way the looper slide block makes two up and down motions for one turn of the shaft 110 and of the shaft 129 hereinafter referred to. The slide block must be shifted across the machine in order to carry the new loop across to the accepting point and back and for this purpose the slide block 111 moves up and down in another slide 130, and the slide 130 carries a rack bar 131 (Figs. 11, 13, 20) which is reciprocated by a toothed sector 132 mounted on shaft 133. Lever 134 connects with the link 135 which is connected to lever 137 which is under the control of spring 136 which normally urges the sector anti-clockwise (Fig. 20). The lever 137 has a bushing 224 and a stop collar 225 so that it is axially held but can rock on a shaft 138 which is borne by the machine frame. The shaft 138 is slideable in the bushing 224 and carries a fork 139 which engages a grooved member 140 on the spindle 141 to which a roller 142 is fast. On the shaft 129 there are two cams 143 and 144, the roller 142 being shown in operative relation with the cam 144. In this position of the parts, the cam 144 displaces the roller 142 throwing upwards the lever 137 and the rod 135 which turns the arm 134 on shaft 133 and thus imparts the movement to the toothed sector 132. In this way the looper slide 130 is brought across to that side of the machine which will allow the looper to be brought into co-operation with a guard member.

During the travel of the slide 130, the rack 112 carrying the looper bearing 18 is being lowered through the mechanism from shaft 117 previously described. Shaft 101 is then timed to oscillate. In this way shaft 98 is also caused to turn through the gears 100 and 99 and the spindle 15 also receives its turning motion through gears 17 and 16 and the looper spindle and looper through gears 14 and 13 are caused to turn according to the direction in which the shaft 101 is turning so that the hook of the looper will enter through the stitch about the guard member and a plain or purl stitch will be drawn accordingly. The shaft 117 then turns back and the timing arrangements are such that when the looper has passed through the old stitch with the new loop, the slide block 111 rises, the old stitch is thereby removed from the guard member and the slide block 130 moves back across the machine by the action of spring 136 and 75

under the control of the cam 144. In this way the looper is caused to carry the newly drawn loop across to the accepting member. Motion of eccentric 126 then turns the shaft 117 in such direction that the slide block 111 and thereby the looper, will be lowered thus depositing the new stitch on the accepting member.

The slide 130 is slideable transversely of a frame 145 which is movable along screw guides 147 for the purpose of varying the distance between the frame 145 of one knitting station and that of the other knitting station which for the sake of simplicity is not shown, since it merely involves duplication of the mechanism shown at the left of Figs. 10 and 11 at the other end of the machine, with the second looper and threadlayer arranged to carry the new loops across the machine in the reverse direction, as hereinbefore stated, the bevel gears 100 and 116 being slideable along key-ways 100a and 116a. In this way the effective number of conveying members may be varied. Various of the shafts may be so key-wayed to allow of movement of parts therealong as hereinafter described.

Provision may be made as hereinbefore described for displacing the thread-layer to lay the yarn across the hook of the looper or a slight axial movement may be given to the latter to enable it to engage the thread, as by providing a depression 143a and a hump 144a on cams 143,

Inasmuch as the machine being described is designed to knit plain and purl selectively whether for tubular knitting or flat knitting, we will first describe how the conveying members are displaceable first in one direction and then in the opposite direction along the track. On the shaft 110 are two eccentrics 148, 149 (Figs. 11 and 20) and each of the straps 150, 151 of these eccentrics has its other end arranged as a pawl 152, 153 engaging ratchets 154, 155. One pawl is operative at any one time and the other merely slides about a shield 156. When it is required that the other pawl shall become into operative position, the shield is given a part turn in the manner hereinafter described, so that the first pawl then slides over the shield and is ineffective. One pawl may therefore be used to operate the ratchet shaft 157 in one direction, the other pawl to operate it in the reverse direction, so that the worm 96 which drives the sprockets 5, 6 which operate the conveying members may be rotated in either direction.

The conveying members may be mounted in a travelling endless conveyor belt or chain or the like instead of pushing each other round an endless track. For example they may each have a reduced stem slideably mounted in a bearing tube on the endless conveyor.

If desired the conveying members may be slid up or down, e. g., in the manner described in said prior application Serial No. 351,622 for the purpose of casting off the old stitch and/or entering the new loop.

In order that the machine may knit either plain or purl, under automatic control which involves changing the direction in which the looper hook passes through the old stitch and changing the disposition of the thread layer and in order that the direction of flow of the knitting may be reversed a jacquard mechanism is provided in the machine.

This mechanism comprises a rotary cam 159 (Fig. 10) on shaft 129 engaging a projection 160 from a slideable shaft 161 carrying at one end a

ratchet 162 with which engages a pawl 163 whose axis is fixed, the ratchet being on a shaft 164 carrying sprocket wheels 165 which drive a jacquard band 166 which has two rows of perforations.

With each rotation of the rotary cam 159 on shaft 129, the shaft 161 reciprocates and when such shaft is moving to the left of Fig. 10 the ratchet wheel 162 turns in an anti-clockwise direction whilst it is moving with the shaft. There are a series of perforations 163a along the band and so long as the perforations successively engage over a projection 164b on the end of a lever 164a when the drum is brought towards said lever the latter remains fixed. There are two such levers 164a in the machine however and when perforations in the band register with the projections 164b the levers remain in operative locking engagement with the tail arms 165a and 166a of levers 167 and 168. When however a predetermined change in the knitting, i. e., from plain to purl or in the direction of flow is required, a perforation will be omitted from one or both series along the band and one or both of the levers 164a will be turned, thus releasing the other lever 167 or 168 for operation by springs 167a and 168a. The lever 167 controls the direction in which the looper passes through the old stitch, or in other words, whether there should be a plain or purl stitch knitted.

When the lever 167 is released it is urged by spring 167a in a clockwise direction against plunger 169 which is continuously reciprocated by a cam 170 on shaft 171 driven from gearing 121, 171a, through the medium of roller 172 on a projection on the plunger, the plunger normally having no effect on the lever so long as the latter is held locked by lever 164a but when it has been released by the latter lever and is urged by the spring against the plunger, the latter throws the lever round and this lever, through pawl 173 thereon, drives round one step, a ratchet wheel 174, which is fast with the drum 175. The drum has a disc 176a with a series of cam teeth 176 (only one is shown in Fig. 10) spaced around its periphery and these teeth co-operate with plunger 176b which has an arm 177 (see Fig. 11) which carries an upstanding fork 179 which engages a grooved collar 179 on a spindle which carries the roller 109 so that in one position of the plunger (see Fig. 14), the roller 109 engages the cam 107 and in the other position of the plunger it engages the cam 106. In other words the plunger will cause the roller to engage one of the cams 106, 107, when it is engaged with the top of one of the cam teeth 176 and to engage the other of such cams when it moves down such cam tooth to the limit determined by the forked end of rack 103.

The other two cams 104, 105 are brought into operation by the second lever mechanism 164a and 168 and the common plunger 169. When a second ratchet wheel like that 174 but on a second drum 217 (Fig. 11) is turned through the operation of the lever 168 shaft 138a is engaged by radial teeth like those 176 but on disc 216a and displaced, this shaft carrying a fork 139a (see Fig. 21) which engages a grooved member 140a which is carried by a bushing to which the four cams 104, 105, 106 and 107 are connected and therefore the cams themselves are displaced sufficiently to take the cam pair 106, 107 out of action with respect to either position of roller 109 and to bring one of the cams 104 or 105 into engagement with the roller 109. The cam pair 75

which is brought into juxtaposition to the roller will depend upon whether the plunger is engaging with the top of the cam teeth or the bottom of such teeth. The roller 109 is displaceable from one to the other of the cam pair 104, 105 just as it is from one to the other of cam pair 106, 107. The cams are rotatable on shaft 110 (see Fig. 14) but are capable of being moved axially along such shaft by means of the key and key-way device 180, 181 through which the drive is transmitted. In Fig. 15 the cam 104 is shown in operative relation to the roller 109 and Fig. 16 shows the looper lowered and in a neutral position. The roller 109 is contacting with the circular part 182 of the cam and it is to be observed that each of the four cams has a similar circular part 182. Bearing in mind that the spring 108 (Fig. 14) is urging the rack 103 and roller downwards, the rotation of the cam 104 in the direction of the arrow A to bring part 186 to the roller will have the result of allowing the looper to turn in the same direction (see arrow B of Fig. 16) thus relating the looper to the conveying member on the right-hand side of that figure, which member will serve as the guard. Further movement of the cam beyond the hump 183 will allow the spring 108 to bring the roller to the lowest part 184 of the cam and give the looper hook a turn through the guard to engage the thread. Further rotation of the cam now brings the thicker part 185 of the cam into engagement with the roller so that the looper hook will then receive a reverse turn through the guard carrying with it the new loop. When the change is from plain to purl and the cam 105 has therefore been brought into operation, the roller 109 will start at the top position and through the portion 186 will receive a turn similar to that allowed by the correspondingly shaped portion of cam 104 to turn the looper into the correct knitting relation to the guards on the right-hand side of Fig. 16, but instead of the roller then passing into a hollow in the cam as in the case of the cam 104, it contacts with the hump 187 of the cam 105 and is thus turned in the opposite direction through the guard to engage the thread and subsequently when the roller reaches the falling away part 188 of the cam, returns with the new loop. When the flow of the knitting has been reversed as will be hereinafter explained, one of the cams 106, 107 comes into operation. As cam 106 engages roller 109, the falling away part 186 which characterises the cams 104, 105 is replaced by hump 189 with the result that the initial turn of the looper is towards the conveying members on the left of the Fig. 16 so that the looper is then turned into knitting relation with those members which will then serve as the guards. This same hump characteristic is present in the cam 107 but cam 106 has a hollow 190 to allow the spring to turn the looper hook first in one direction to engage the yarn whereas the cam 107 has a further hump 191 which will cause the looper first to penetrate the guard to cause the looper hook to engage the thread in the other direction. The thread layer must be displaced, depending upon whether a plain or purl stitch is to be knitted, and depending upon the direction of flow of the knitting.

Referring to Figs. 22 to 24, the thread layer 146 (see also Fig. 12) is provided with two bosses 192 and 193 which are slidable along two cross rods 194 and which are fixed to spaced racks 196 which are guided in the looper frame 145 and which are driven by pinions 199 and 200 on shaft

201 which is provided with a bevel wheel 202 driven by a bevel 203 on the shaft 204. The motions of the shaft 204 are derived from the Jacquard mechanism in the following way. The shaft 204 (see Fig. 10) has a pinion 205. A rack 5 206 engages such pinion and is displaced by means of a lever 207 through pin connection 208 the lever being pivoted at 208a. The lower end of the lever 207 is operated upon by cam teeth 209 on the side of the disc 176a of drum 175 (Fig. 11) and there are the same number of such cam teeth around the drum to operate the thread-layer as there are teeth 176 on the disc 176a for operating the plain and purl mechanism so that as the drum receives its motion to alter the direction of penetration of the looper through the stitch, so also is the thread-layer brought into thread-laying relationship therewith. In Fig. 22 the thread-layer is held to the right of the figure by the lever 210 against the urge of springs 211 (Fig. 24) arranged in the bosses 192 and 193 which carry the thread-layer. When the direction of the flow of the knitting is to be reversed, the thread-layer should be drawn over by the spring means from the right-hand side of Fig. 22 to the left, which involves rocking the lever 210 out of obstructing relation to a plunger 212 on the thread layer. This rocking motion of the lever 210 is achieved by mounting it on a shaft 213 carrying a pinion 214 which is engaged by a quadrant 215 which in turn is rocked by cam teeth 216 (only one being shown) arranged on disc 216a of the second Jacquard drum 217 and operative similar to the teeth on the former drum, that is to say when the quadrant is engaged by the top of the teeth, the lever 210 must be in one position and when engaged by the bottom of the teeth the lever will be in the other position.

With the modified apparatus shown in Figs. 10 to 24f, new loops may be formed in the same way as is described with reference to Figs. 9a to 9l, the threadlayer being in the upper position M, see Fig. 24b, and we will now describe how new loops may be formed through the old stitches at any time under the control of the Jacquard mechanism in the reverse direction so that plain and purl effects can be obtained. Assuming cam 104 to have been in operation with the thread-layer in position M. Now, if the next new loop is to be formed through the next old stitch in the reverse direction to the last new loop through the last old stitch, the roller 109 will be displaced from engagement with cam 104 into engagement with cam 105 by the Jacquard release of trip mechanism 167 allowing plunger 169 to operate lever 161, pawl 173, ratchet 176 and drum 175 thereby to cause a cam tooth 176 to shift plunger 176b and through arm 177 (Fig. 11) carrying fork 178 which engages grooved collar 179 on the spindle carrying roller 109 to displace said roller.

The threadlayer 146 is moved down through the Jacquard mechanism operating cam teeth 209 on drum 176 and thereby shifting lever 207 (Fig. 10) and through the pin 208 displacing rack 206 to operate pinion 205 and turn shaft 204 and gearing 203, 202 thus turning shaft 201 carrying gear 199 and 200 engaging rack 196, thus lowering the said rack carrying the threadlayer from the position M Fig. 24b to position M'. The depresser 75 previously referred to is moved to displace the thread and fabric as described in regard to Figs. 9a to 9k so that the looper hook 12 can enter freely into the old stitch.

While these operations are taking place, the

slide 111 is being carried across the machine to the right by the operation of cam 143, levers 131, 135 and 134, and segment and rack gear 132, 131 and is moving to the right Fig. 20, roller 109 being on the upper circular part of the cam 105 (Fig. 17) while the looper is in raised neutral position (see Fig. 24a) in its bodily travel across the machine from left to right, the hooks of the looper being directed downwards neither towards one side or the other of the machine.

Eccentric 126 through lever 127, rack 119, pinion 118 operating shaft 117 carrying pinion 113 engaging rack 112, lowers the slide 111 carrying the looper as this slide is moving to the right and when the looper is reaching its lowermost position to the right that part 186 of cam 105 will start an initial turn of the looper to direct both hooks towards the right, as shown in Fig. 24b. When the looper is about at the limit of its movement towards the right and at its lowest position, the upper edge of hump 187 of cam 105 will turn the looper to take hook 12, i. e., the other hook to the one which was operative in Figs. 9a, etc., through the old stitch about the guard 1a, see Fig. 24c. The cam 143 displacing slide 111 to the right is now in such a position that the roller 142 is spring pressed by spring 136 into the depression 143a thus giving to the slide 111 and therefore to the looper and sharp movement back over the thread from the thread layer (to positions Fig. 24d) which thread lies at an angle across the machine as shown in Fig. 24d without engaging said thread. The roller 109 will then fall down the other side of the hump 187 by the action of spring 108 and the turn back of the looper hook 12 will commence and at the same time the continued rotation of cam 143 will force roller 142 out of the depression 143a, thereby sharply moving the looper back towards the right so that the hook 12 engages the angled thread in its turn back and carries the thread as a new loop through the old stitch (see Fig. 24e). The looper slide now commences its return movement across the machine under the action of cam 143 and is simultaneously moved by the eccentric 126, lever 127, rack 119, pinion 118, shaft 117, pinion 113, rack 112 aforesaid first upwards until the highest position of the looper slide is reached, and then downwards so that the looper is carried down and deposits the new loop Y on the empty conveying member on the left hand side of the machine (see Fig. 24f), Fig. 29e showing the old loop X starting to be pulled off member 1a and Fig. 29f showing it released from said member.

The circular bottom portion 188 of the cam 105 meanwhile has been keeping the looper from oscillating. Now the opposite hump corresponding to 187 turns the looper to free it from the landed new loop, the slide meanwhile rising so that the looper clears the landed loop in completing its oscillation and when the hump has been passed, the part of the cam to the left (Fig. 17) corresponding to the part 186 to the right returns the looper to neutral position (with both hooks pointing downwards) while the slide 111 moves back to the right again, circular part 182 of the cam then coming into operation to keep the looper in neutral position until the next looping operation is to be achieved.

With the loop free from the landed loop the pawl 151 will turn shaft 157 carrying worm 96 (see Fig. 11) to shift round the conveying members one step thus bringing a member with new guarded stitch into position to work with the

looper and a new empty accepting member from the reserve members also into position, while the guard from which an old loop has been drawn off passes into reserve and the member which has accepted the new loop moves on and after a number of stepwise displacements round the machine will itself be positioned to co-operate with the looper for a new loop to be formed through the loop thereabout.

In order as previously described that the shield 156 may be automatically given a part turn so that whichever of the pawls 152, 153 (Fig. 20) that has not been in use can now come into operation, the shield is rotatably supported and from it projects a lever 218 having a projection 219 which projection is engaged by a lever 220 which cooperates with a series of radial teeth 221 upon the disc 222 on the second cam drum 217.

When the direction of knitting has been reversed, the looper now cooperates with the members acting as guard members which previously served as the accepting members and the motion of the looper slide 130 must be reversed and this is similarly effected by the jacquard control, the cam drum 217 having a third disc 223 provided with a series of radial teeth arranged to shift the shaft 138 so that through the fork 139 and the grooved collar 140, the shaft carrying the roller 142 is displaced and the roller 142 is taken out of operative relation to one of the cams 143, 144 (Fig. 20) and is brought into operative relation with the other of such cams. The shaft 138 as before described is slidable with respect to the lever 137 which has a bushing 224 held against axial displacement by collar 225.

In the forms of machine illustrated in Figs. 25 to 34, the guard members and accepting members are mounted transversely in closely spaced relationship along two separate endless conveyors 226, 227 so that the one series of conveying members for the time being carrying the stitches on one conveyor travel in one direction see arrow X Fig. 29 in a substantial horizontal plane with the channel 2 or other guard-forming parts uppermost, towards the knitting station or towards one such station and away from another, and are then turned over in the course of travelling round sprockets 228, 229, of the conveyors so that they move horizontally with the channels facing downwards. The series of conveying members on the other conveyor, travelling in the direction of arrow Y and also driven by similar sprockets 228, 229 have the same movement but in the reverse direction. A looper 9 towards one end of the system knits across from one conveyor to the other and a second looper towards the other end knits from the second conveyor to the first. The second looper and associated mechanism is a duplication of that described, except that such looper knits from the second conveyor to the first, and for the sake of simplifying the description and drawings, the said looper and associated mechanism are not shown. The conveying members may be each pivotally mounted in channelled guides 230 (Fig. 26, 33, 34) in or on the conveyor in such a way that they can pivot in the guides and also receive a movement along the guides and transversely to the direction of motion of the conveyor in order to produce a movement of the conveying members towards and away from each other for knitting. For this purpose, the conveying members may be in the form of two-armed levers the fulcrum being formed by sloping away the base portion of the member from a central fulcrum

232. The guard portion is formed near the end of the forward arm 233 of the lever. The new stitch is accepted by a sharp or pointed end 234 of the forward arm of the accepting member, the pointed tip moving in close juxtaposition to the hook of the looper 9 while entering a new stitch. The looper axis may be displaceable to aid the knitting process, but in the form illustrated it is fixed and the looper receives only an oscillating action about such axis.

Normally the forward arms of the conveying members which are carrying stitches may rest upon the base of the channel of the guide, those 1a, 1b, 1c which are to serve as guards, approaching the knitting station or stations and moving in progressively or step-by-step (see Figs. 29 and 30). The conveying members 1m, moving up to the knitting station to accept a new stitch may have their forward ends raised. At or near the knitting station, the forward arm of the stitch-carrying member which is about to act as guard, is rocked upwards so that the guard is brought below the stitch former 9 and the channel in such guard member is in such a position in relation to the stitch former that turning movement of the latter about its axis carries a hook end of the said member through the channel into a position to engage the thread which is appropriately laid by the thread layer 235, whereupon the stitch-former is turned back in the reverse direction so carrying the thread through the channel and the old stitch thereabout. The old stitch-carrying member is then rocked by depresser 236 to depress its forward end whilst the thread of the new loop is held on the hook so that the new loop is drawn out completely and whilst the new stitch is still held on the hook, the forward arm of the member 1e which is to accept the new stitch is moved inwards, between the depressed forward end of the guard member and the hook and in near relation to both and into the new stitch, by the slide bar 237 engaging a projection 238 on the conveying member. Another part turn of the stitch former, if desired synchronised with the return movement of the accepting member, releases the thread from the hook and the accepting member moves a step outwards and the stitch former is returned to its original position. The accepting members may be moved outwards progressively, or by a series of steps, outwards, say as shown, corresponding to the inward steps given to the guard member, in moving further round with the conveyor.

After the conveying members have been respectively moved into the new and out of the old stitches, the conveyors are moved on so that a further stitch is brought to the knitting station by one conveying member and the newly formed stitch is carried towards the knitting station at the other end of the machine by the other conveying member, where it has a further stitch formed through it which stitch is accepted by a conveying member on the first conveyor. The conveying member withdrawn from the old stitch will pass along with the conveyor 226 in the direction of arrow X (Fig. 29) and round the sprockets, being displaced to such a position as to cause little or no interference with the fabric, and then being brought back into the top reach of the conveyor to act as an accepting member at the other knitting station.

The knitting ends of the stitch conveying members may be of chisel-wedge form 238a with the corners of the wedge chamfered at 239 to reduce the edge to point 234 to facilitate entry through

the new loops and they may taper at 240 from the widest part of the wedge rearwardly from the wedge in order to promote the safe retention of the new stitch and the casting off of the old stitch. The latter step may be facilitated by providing a stop or presser member 241 (Fig. 28) to hold back the knitted fabric whilst the conveying member is receding out of the old stitch. This member 241 is merely a vertical plate or verge which lies against the fabric near the knitting station so that as the guard member is retracted from the loop thereabout, through which the last new loop was formed, the retracting guard member shall not be able to draw back its loop with it and shall not try to force the adjacent guarded loop or loops back along their guard members. The accepting members in moving from their forward accepting position back into the normal line of movement may tend to move out of or partly through the accepted loops, and in order that these loops shall be retained in the predetermined accepted position on the members, a thin horizontal cam plate 242 (Fig. 29) is disposed immediately under the members, said plate having inclined operating edges substantially parallel to the general inclined line in which the leading ends of the accepting members move from their fully forward position back into the aforesaid normal line of movement. Camming means 242 (Fig. 29) are incorporated for assisting in holding the new stitch on or forcing it along the accepting member whilst this is receding from the knitting station. The channeled head may have local enlargements 243 which bring the adjacent members in to abutting relationship.

Each conveyor comprises two (or more) spaced chains 244, arranged to travel in an endless path around the spaced sprocket wheels 228, 229 each pair of sprockets of one conveyor being co-axial with those of the other. The guides 230 in which the conveying members are slideable and pivotal bridge the two chains and are carried round thereby.

Several of such guides may be in a block and the block welded or otherwise secured to the links of the chains, but preferably, as shown, the guides are separate members mounted on the chain links. Each chain is of the roller variety with the rollers 245 bridging each end of a spaced series of inner links 246 which are joined by overlapping outer links 247 the rollers being borne by spindles 248 mounted in the overlapping parts of the links. The outer edge of each link has a series of outwardly projecting fingers 249 which engage in U-shaped grooves 250 formed externally around the channel guides 230. The overlapping parts of the links are spaced and the grooves 250 in the bridging member 230 are made only of the width of one finger and in order inter alia to preserve standardisation of the guides for the different parts of the chain, four grooves may be provided at each end of the guide member (see Fig. 34). Two of these grooves will engage two fingers. The guide channels may be formed from long strips of suitable gauge steel slotted at 251 locally along the longitudinal axis and provided with four transverse grooves near either end. This member is bent to U shape about the central longitudinal axis so as to bring the grooves which receive the fingers to the exterior, and the slot along the bottom of the channel, although the grooves need not necessarily extend around the bottom of the channel (see Fig. 34).

The distance (a, Fig. 32) between the centre lines of the two end fingers of each link may be equal to that between the two roller centres of each link, and each link may carry an equal number of fingers, e. g., four as shown, so arranged that the two end fingers and the corresponding end finger of the next preceding and succeeding links wholly overlie, although spaced by collar 252. Two of the grooves at each end of the guide will not be occupied except where the links overlap. In order not to space the conveying members unduly the grips from which the channel guides are made, are as thin as possible consistent with allowing that depth for the grooves into which the finger projects which will permit the fingers to be of sufficient strength. The guides may be brought into contact or very close relationship one with another.

When the fingers travel around the sprockets the end fingers tend to move out of the grooves in the guides and in order to facilitate their re-entry the edges of the fingers may be bevelled or chamfered, e. g., as shown at 253 to cam their way back into the grooves.

The firm retention of the conveying members in the guides may be promoted by a frictional grip between them and the guides as by making the conveying members act in the manner of a blade spring.

Means such as bars 254 may be provided, for preventing the conveying members from falling out of the guides when the latter are inverted in travelling with the lower reach of the conveyor and such means may extend around the portions of the chains on the sprockets.

Thinner projections 238 from the lower part of each conveying member pass through a narrow slot 251. A second slide bar 255 engages with this projection on the guard for giving the member a sharp movement out of the old stitch. There is also an upper projection 256 from the guard members co-operating with cam 257 for giving to the guard member the movement towards the accepting member and a corresponding projection 256 from the accepting member for giving the accepting member the movement away from the guard member by means of cam 258, and two further projections 259, 260 may be provided one, 259, on the tail portion of the conveying member and the other 260 on the forward portion of the member which are engaged by depressers 261, 262 to rock such member when it has reached or is approaching or receding from the knitting station.

The loopers are each on a carriage 262a movable parallel to the path of movement of the upper reaches of the conveyors along guide rods 262b in order to bring more or less of the stitch conveying members into operation. This form of machine like the first machine described may be modified so that operations, such as changing from plain to purl and reversing the flow under the control of Jacquard mechanism, can be effected. The conveyors are moved intermittently by ratchet and pawl device 263, 263a the pawl being on the sleeve of eccentric 263b on shaft 263c driven through gearing 263d, 263e from the main shaft 43a of the machine. Worm drive 264, 265 transmits the motion to the chains. The timing of the conveyors is generally such that the conveying members of one conveyor are directly opposite to those of the other and the normal operation of the intermittent mechanism is such that each conveyor is displaced by one conveying member at a single displacement.

With the conveying members in the present form we may mount the looper on a fixed axis so that it just oscillates and for simplicity we have indicated the looper spindle 10 and the spindle 15 corresponding to that in the previous forms of the machine which drives the looper spindle by a bevel gear as before and is itself driven by worm gearing 16, 17 and shaft 308 and which can be operated from the shaft 309 of gear 296 by cam 310 lifting a slide 311 and rocking the arm 312, a spring 313 effected the return movement. The thread layer 235 is mounted to rock on spindle 314 being shown in Fig. 27 as being swung into a position in which the hook of the looper can pass freely without engaging the yarn and being then displaced by the arm 315 in a clockwise direction to enable the hook when returning to engage the thread and draw the loop. This movement of the arm 315 is effected by providing its shaft 316 with a pinion 317 which is driven by a rack 318 by the medium of cam 319 operating the roller follower 320.

In all cases in this layout, the cams are drawn diagrammatically.

As the guard members move up to knitting position, the forward arm is rocked up by depresser 259a acting on projection 259, this depresser having a rack 270 operated by pinion 271 on a shaft 272 containing a second pinion 273 which is geared to rack 274 which has a roller 275 operated by cam 276.

The guard is given a progressive inward movement by cam 257 co-operating with projection 256. The looper having been given a part turn to engage the yarn and a reverse part turn to draw the loop through the channel, depresser 261 lowers the forward arm of the guard while the loop is held by the looper, by acting on projection 260, this depresser having a rack 277 co-operating with a pinion 278 on shaft 279 having a second pinion 280 operated by rack 281 with a roller operated by the second cam hump 283. The shaft carrying these two cam humps is driven through gearing 284, 285 and 286 from the main shaft.

Reserve accepting members move up to the knitting position and the forward arm is raised by depresser 262 co-operating with projection 259 and racked so as to be operated by pinion 281 on shaft 288 carrying second pinion 289 driven by rack 290 through roller 291 and cam hump 292 on cam 293 driven through gearing 284, 285 and 286 from the main shaft. With the guard lowered as before described and the accepting member so raised, slide 237 is now operated through the leverage 297, 298, 299 and 300 and cam 301 to move the accepting member inwards over the guard member and through the new loop. The looper is now given a second oscillation to disengage the loop. The guard is now retracted from the old stitch by slide 255 displacing projection 238, the slide 255 being operated through leverage 302, 303, 304 and 305 by cam 306. The member which has accepted the new stitch is now moved outwards progressively by cam 253 operating on projection 256 and the projection 260 which has been thrown forward with the accepting member and is now receding strikes cam surface 307, thereby lowering the forward arm of the acceptor into its normal position.

Drums 350 with V notches 351 may be mounted on the sprocket shafts of the conveyor (see Fig. 25) and V plungers 352 arranged to engage therein, this ensuring that the conveyors shall be held

in correct position after each displacement and the two operative guard and accepting members therefore positively located at the knitting station.

The upper reach of each chain and also the lower one if desired may be prevented from sagging by suitable bars 230a over which the chains or the guides may slide or the rollers may run on fixed tracks or the roller spindles may be extended and bear additional rollers to run on supporting tracks.

Figs. 35 to 40 show diagrammatically another construction of machine in which there are two endless conveyors, each driven by sprockets 228, 229 (only one conveyor being shown in Figs. 38-39).

Each series of conveying members 1 travels along an endless track comprising two endless plates 310 one within the other, the conveying members being mounted to travel between such

20 plates and being of angle, preferably L form as shown with the horizontal and longer limb 311 or shank between the plates and the other limb 312 outside the plates. Such outer limb is channeled or slotted at 2 or otherwise made to function as the guard so that the looper 9 can enter the guard from the side nearest to the opposite accepting point. In other words the channels in the members in the opposite reaches or systems face one another.

25 The looper 9 may be arranged to oscillate and have transverse and vertical movements as in the first form described, one hook of the looper, the hook 11 in this case, being arranged to pass through the stitch about the conveying member which is for the time being the guard member on the left conveyor and back in order to engage the thread, draw the new loop and then rock across the system and move down over the point of an opposite conveying member which is to be the accepting member. When the loop has been carried through the old stitch the guard conveyor member is rocked out of the old stitch, e. g., as described in reference to Figs. 25 to 34, aided in this form by the tendency of the looper to draw off the stitch about such member. The accepting member rises into the new loop, when this is being carried over by the looper into a position in which it can be readily penetrated by the rising member. When the new loop has been landed the opposite reach or system of conveying members and the conveying members are advanced.

30 The desired motion of the conveying members around their respective tracks may be achieved by shaping the lower edge of the conveying members at 313 to gear at each end of the track with the two sprocket wheels.

35 The short limb or guard part of each conveyor member may be shouldered laterally at 314 to assist in supporting the old stitch while the new loop is being carried through it. The looper operates with this form as it does with the first form described.

40 In the form of the machine illustrated in Figs. 41 to 45, the conveyors may be fixed, or replaced as shown by two fixed beds 401, 402 of conveying members, and the looper arranged to travel longitudinally of the beds to knit off the fabric from one bed to the other and then reversing to knit back to the first bed. This can be very simply achieved by arranging the looper frame 262a to be slid able but under the control of a ratchet or other step-by-step mechanism so that

the frame advances step-by-step and any suitable clutching or reversing means may be employed to reverse the frame when it has reached the end of its stroke.

In this machine, see Fig. 41, we provide the depressors 259a, 236, 262 (like those in Figs. 26 and 27) and a further depressor 350 hereinafter referred to, which together with the looper and thread-layer are mounted on the sliding carriage 262a which is movable along the screw rods 262b, and the mechanism for operating the slides 237 and 255 is also transferred partly to the looper carriage. The slides 237 and 255 are in this form provided with two spaced projections 351, 352 and they are operated by arms 353 slidably keyed to shaft 354 carrying a second arm 355 connected by link 366 to a lever 377 pivoted at 388 to the machine frame and carrying a cam follower 389 which is arranged to be related to cams 390 and 391, only one of which is operative at any one time, depending upon the direction in which the looper frame is travelling along the machine. On the shafts 272, 279, 288 and the further shaft 392 operating the depresser 350, the pinions 273, 280, 299 and 393 are keyed so as to turn therewith but so as to be slidable therewith along the looper frame and the arms 353 are similarly mounted so as to be slidable along shafts 354, the levers 355 being fixed to such shaft at one end of the machine.

The arms 353 are normally held in a neutral position as shown in Fig. 41 by springs 394 and the slides 237 and 255 may be located in neutral position by means of the spring urged plungers 395.

The looper 9 is driven through spindle 15 and worm gearing 16, 17 and shaft 308 by a similar mechanism to that shown in Fig. 27 and a thread layer similar to that shown in such figure is also included, but arranged so as not to interfere with the mechanism for operating the depresser 350.

Assuming the guard members to have their forward arms raised. The looper will be operated to oscillate and draw a loop through the raised guard member. The latter is then lowered by depressers 236 acting on projection 260, a depresser 350 being simultaneously lowered but having no action on the accepting member since the projection 260 has not been brought beneath it. The depressers having now risen the guard remains frictionally held depressed the raised accepting member is thrust inwards by the slide 237 acting on the projection 238 through the new loop. The guard member is then retracted out of the old stitch by the projection 352 thrusting on the projection 238 of the guard. When the looper frame reaches the end of its stroke, and commences to return, it must now knit from the raised accepting members now to serve as the guards onto the lowered guard members which now act as the accepting members. The reversal of the stroke of the looper carriage is effected by the clutch mechanism hereinafter described, and the guards are successively raised by depresser 259a.

The thread layer 418 and its relation to the looper is shown diagrammatically in Figs. 42 and 43. In its full line position, Fig. 43, it is in such a position that the looper hook can travel through the guard free from the thread. Before the looper hook returns the thread layer is given a turn about its axis 419 in a clockwise direction so that the looper can engage the yarn and carry it through the old stitch around the guard. When

the direction of travel of the looper frame is reversed the thread layer must start in the dotted line position, the same looper hook can then turn through the guard free from the thread whereafter the thread-layer is then rotated in an anti-clockwise direction so that the hook in returning through the guard can engage the thread and carry it through the old stitch. The shaft 420 carries a helical gear 421 engaging a similar gear 422 on the thread-layer spindle 419 and the gear 421 is keyed to the shaft 420 so as to be slidable therewith along the looper frame. Means may be provided, e. g., a shifting cam, for reversing the oscillation of the shaft 420 when the looper carriage is reversed.

Now that the looper carriage is to return the cams 390 and 391 are now reversed so that the cam 391 which has been operating the slide 237 for inserting the accepting member is now taken out of action and the cam 390 brought into engagement with the follower 389 of the lever 377 and the cam 390 which has been operating the slide 255 for retracting the guard member is now displaced out of the path of the roller 389 of the corresponding lever 377 on that side of the machine and the cam 391 brought into operative relation therewith. Then the same cycle of operations of the various depressers will take place as previously described but with the members on the right-hand side of Fig. 41 now acting as guard members and those on the left as the accepting members.

The reversal of the looper frame at the end of each stroke is by the mechanism shown diagrammatically in Figs. 44 and 45. The rods 262b along which the looper carriage moves by screw action carries a spur wheel 402 gearing with a second gear wheel 403 on a stub shaft 404, each shaft having one member 405, 406 of a jaw clutch. With these clutch elements co-operate the companion clutch elements 407 and 408 which are slidably mounted in a fixed guide 409 and which are toothed at 410 and 411 to form pinions for gearing with rack 412 which is reciprocated by eccentric connection 413 on the shaft 414 which is driven from the main shaft. Only one clutch element is in engagement with its companion part at one time and when at the end of the stroke of the looper this element is disengaged and the other element is engaged, the rotation of the shafts 262b for the carriage will be reversed due to the gearing 402 and 403. The slide clutch elements are each provided with a grooved portion engaged by the forked end of a lever 415 the other arm of which co-operates with a series of cam teeth 416 on one of the cam drums controlled by the Jacquard mechanism as in the previously described machine.

There will be two such levers 415 one for each slide clutch element and two cam discs, the cam teeth 416 of one being circumferentially staggered with relation to the teeth 416a of the other so that when the teeth-engaging end of one lever is on the top of a cam tooth the slide clutch element is thereby withdrawn. The corresponding end of the other lever will then be at the base of the cam teeth of the other disc, thereby causing the lever to hold at the slide element into engagement with its companion lever. Springs 417 normally urge the clutch elements into engagement. A stepwise rotation of the cam drum turns the other lever onto the top of the cam and allows the first lever to fall to the bottom of the cam teeth.

This same mechanism may be used for revers-

ing the traverse of the conveyors in the travelling conveyor form of the invention. In this case worm wheels will of course be provided to co-operate with the screw on the rods.

According to a modified form of a machine generally operating in the manner of that shown in Fig. 41, for example, the looper may work with a single series of guard members which also act as accepting members, each new loop being accepted by the guard carrying the stitch through which it has been formed. Thus in lieu of an opposite accepting member accepting the new loop, the guard member after having elongated the loop (Fig. 46) may be retracted out of the old stitch and then raised (Fig. 47) and inserted into the new loop (Fig. 48). The looper will then release the new loop and subsequently form a new loop through it when it travels along the machine in the reverse direction to knit the next course.

What we claim is:

1. A knitting machine comprising looping means and a series of stitch guard members, said looping means being constructed and arranged to engage the thread and form a new loop through a previously formed stitch while this is held open around one of said members, means for causing said looping means so to co-operate successively with members of such series and the stitches thereabout, means operative to cause the transfer of the new loops from the looping means to members of said series as new stitches in turn to be held open for further new loops to be formed through them by the looping means, and means operative to cause the release of the previously formed stitches from the members.

2. A knitting machine comprising looping means and a series of stitch guard members, said looping means being constructed and arranged to engage the thread and form a new stitch through a previously formed stitch while this is held open around one of said members, means for causing said looping means so to co-operate successively with members of such series and the stitches thereabout, means controlling the operation of the looping means to enable said means to form a loop selectively in either direction through the stitch to be penetrated, means operative to cause the transfer of the new loops from the looping means to members of said series as new stitches in turn to be held open for further new loops to be formed through them selectively in either direction by the looping means, and means operative to cause the release of the previously formed stitches from the members.

3. A knitting machine comprising looping means and a series of stitch guard members, said looping means being constructed and arranged to engage the thread and form a new loop through a previously formed stitch while this is held open around one of said members, means for relatively displacing said looping means and said members so that the same looping means so co-operates with different members of said series in succession, means operative to cause the transfer of the new loops from the looping means to members of said series as new stitches in turn to be held open for further new loops to be formed through them by the looping means, and means operative to cause the release of the previously formed stitches from the members.

4. A knitting machine comprising looping means and a series of stitch guard members, said looping means being constructed and arranged to engage the thread and form a new loop selec-

tively in either direction through a previously formed stitch while this is held open around one of said members, means for relatively displacing said looping means and said members so that the same looping means so co-operates with different members of said series in succession, means operative to cause the transfer of the new loops from the looping means to members of said series as new stitches in turn to be held open for further new loops to be formed through them selectively in either direction by the looping means, and means operative to cause the release of the previously formed stitches from the members.

5. A knitting machine comprising looping means a series of stitch holding members and new loop accepting means, said looping means being constructed and arranged to engage the thread and form a new loop through a previously formed stitch while this is held open around one of said members and said new loop accepting means being arranged to accept said loop and means for relatively displacing said looping means and said members and said accepting means, and means for operating said looping means to co-operate with said members in succession for producing loops to be accepted by said accepting means.

6. A knitting machine according to claim 1, in which said member with which the looper is co-operating accepts the new loop.

7. A knitting machine comprising a multiplicity of guard and accepting members, and a looping means, and means causing the looping means to co-operate successively with said members so that at each looping operation one member protects the old stitch while the looping means is carrying a loop therethrough and another member accepts such loop from the looping means, means operative to cause the release of the previously formed stitches, the looping means being operable to form further new loops through the said previously formed new loops while these in turn as new stitches are held open and guarded.

8. A knitting machine comprising a multiplicity of guard and accepting members movable progressively towards a looping means some of said members coming successively with a previously formed stitch into knitting relation with the looping means and protecting the old stitch while being penetrated by the looping means and others of said members successively accepting a new loop, means to release the previously formed stitches from the said first members and means to bring said second members successively to the looping means so that as new stitches the loops thereabout in turn have new loops formed through them by the looping means.

9. A knitting machine comprising a looping means and a series of stitch holding members, said looping means being constructed and arranged to co-operate with one of said members to engage the thread and form a new loop selectively in either direction through a previously formed stitch while this is held open around said member, and means for periodically displacing said looping means to bring the same looping means into knitting relation with members of said series in succession, and means for operating said looping means so to co-operate with such different members, means operative to cause the transfer of the new loops from the looping means to members of said series as new stitches in turn to be held open for further new loops to be formed through them by the looping means, means operative to cause the release of the previously formed stitches from the members, and

means to displace the looping means in the reverse direction for forming the further new loops through the new stitches.

10. A knitting machine comprising a looper and a series of members each constructed to hold open a stitch thereabout, means for laying the thread in position to be engaged by the looper and means for moving the looper to form a loop selectively in either direction through a previously formed stitch while this is held open by one of said members and means for relatively displacing said looper and thread-laying means and members of said series carrying stitches so that said looper so co-operates with said members in succession, means to cause the transfer of the new loops from the looping means to members of said series as new stitches in turn to be held open for further new loops to be formed through them by the looper, means to cause the looper to co-operate with said new stitches, and means operative to cause the release of the previously formed stitches.

11. A knitting machine according to claim 1, in which the looping means comprises at least one hook for drawing the new loop through the previously formed stitch.

12. A knitting machine according to claim 1, in which the stitch guard members are of channel form where the stitch is held thereabout.

13. A knitting machine comprising a looping means and a series of stitch guard and loop accepting members, said looping means being constructed and arranged to engage the thread and form a new loop selectively in either direction through a previously formed stitch while this is held open around one of said members and one of said members being arranged to accept said loop, and means for relatively displacing said looping means and said members so that said looping means so co-operates with said members in succession, said members being constructed and arranged to serve at one time as a guard and at another time as an acceptor, means operative to cause relative displacement between the looping means and said members and enable the looping means to co-operate with said new loops while these as new stitches in turn are held open for further new loops to be formed through them by the looping means, and means operative to cause the release of the previously formed stitches from the members.

14. A knitting machine according to claim 13, in which said guard and accepting members comprise an endless series and the looping means is constructed and arranged to co-operate for knitting with a guard and accepting pair of said members which are separated from each other by others of the series, and means for periodically displacing said members to enable said looping means so to co-operate with other pairs of said members.

15. A knitting machine comprising looping means and two endless series of stitch guard and loop accepting members, said looping means being constructed and arranged to form a loop through a stitch around a member of one series and a member of said other series being arranged to accept said loop, and means for displacing said series so that the pair which has been in knitting operation is replaced by another pair as the knitting proceeds.

16. A knitting machine comprising an endless series of upright guard and accepting members each constructed to hold open a stitch or to accept a new loop, means for laying thread

in position to be engaged by the looping means and for moving the looping means to form a loop selectively in either direction through a previously formed stitch while this is held open by one of said members, another of said members being arranged to accept said loop, means operative to cause the release of the previously formed stitch from the first member and means for intermittently displacing toward the looping means members of said series carrying previously formed stitches and members ready to receive new loops so that said looping means so co-operates with pairs of said members in succession.

17. A knitting machine according to claim 16, in which the guard and accepting members are channeled where the stitches are held open by them to receive a new loop and the channels of the guard members face those of the accepting members, the looping means working between said members.

18. A knitting machine according to claim 1, in which the stitch-guard members are channeled where the stitch is held open thereabout and the top of the channel is uppermost, said guard member being arranged to hold open a previously formed stitch so that the return fold thereof bridges the channel top.

19. A knitting machine according to claim 1, having means for displacing said looping means so that said means casts off the old stitch from the guard member after the new loop has been formed therethrough.

20. A knitting machine according to claim 5, having operating means for said looping means which permit said looping means to deposit the new loop on the accepting means.

21. A knitting machine according to claim 1, having means for displacing a stitch guard member out of the stitch through which the new loop has been formed.

22. A knitting machine according to claim 5, having means for displacing said loop accepting means into the new loop to accept the latter.

23. A knitting machine comprising looping means and a multiplicity of guard and accepting members, means for displacing members of said multiplicity progressively in opposite directions towards said looping means so as to enable some of said members to feed previously formed stitches to said looping means and other of said members to accept the new loops, means for operating said looping means after each progressive movement so that the latter engages the thread and forms a new loop selectively in either direction through a previously formed stitch while this is held open around that one of said stitch feeding members which is in co-operative relation therewith, and means for causing said new loop to be accepted from the looping means by one of said accepting members which is in co-operative relation therewith, means operative to cause relatively displacement of said members and the looping means to bring the members of said series carrying the new loops to the looping means so that as new stitches in turn held open they may be penetrated by the looping means, and further new loops thus formed, and means operative to cause the release of the previously formed stitches from the members.

24. A knitting machine comprising a looping means and a series of stitch guard and loop accepting members, said looping means being constructed and arranged to engage the thread and form a new loop selectively in either direction through a previously formed stitch while

this is held open around one of said guard members and another of said members being arranged to accept said loop, and means for displacing said members so that said looping means co-operates with pairs of said members in succession, means to release the previously formed stitches from said members and means for reversing the direction of displacement of said members and the operation of said looping means so that the looping means now form new loops through those previously formed thereby and so the direction of flow of the knitting is reversed for producing flat fabric.

25. A knitting machine according to claim 2, so constructed so that the number of said members which are to be effective for knitting co-operation with said looping means may be pre-selected so as to determine the width of fabric to be knitted.

26. A knitting machine according to claim 16, in which the travel of the guard and accepting members is derived by constructing and arranging them to form internal gears co-operating with toothed driving wheels.

27. A knitting machine according to claim 1, having a looping means comprising a hook at the end of a curved or bent arm connected to a medial axle or bearing and means for oscillating the looping member about such bearing or axle first to pass the hook through the guarded stitch to engage the thread and then to draw the new loop.

28. A knitting machine according to claim 2, having a looping means comprising an oscillatable curved or bent arm having a hook at each end, said hooks being selectively employable, the one to pass through a previously formed stitch in one direction to engage the thread and draw a loop in the other direction and the other to penetrate a previously formed stitch and draw a loop in the reverse direction.

29. A knitting machine comprising an oscillatable looper and a series of stitch guard and loop accepting members, means for oscillating said looper to cause it to engage the thread and form a new loop selectively in either direction through a previously formed stitch while this is held open around one of said guard members, and means for displacing said looper bodily to enable it to release the old stitch from the guard member and leave the new loop on the accepting member.

30. A knitting machine according to claim 29, in which the oscillatable looper works between upright guard and accepting members and has a hurdling movement from between the said members over the accepting member and vice versa.

31. A knitting machine comprising a series of stitch holding and stitch accepting members and a looping means, means for operating said looping means to form a new loop selectively in either direction through a previously formed stitch while this is held open around one of said members, means for retracting the stitch holding member out of the stitch when a new loop has been formed therethrough, means operative to cause a member to accept the new loop, and means for relatively displacing said looping means and said members so that said looping means so co-operates with different holding and accepting members in succession, and means operative to enable the loops formed by the looping means in their turn as new stitches to be held open and further new loops formed through them by the looping means.

32. A knitting machine according to claim 31, in which said members are constructed so as to serve as holding and accepting members in turn.

33. A knitting machine according to claim 29, in which the guard and accepting members are displaceable to aid the release of the old stitch and the acceptance of the new loop.

34. A knitting machine comprising looping means and a series of stitch-holding members, said looping means being constructed and arranged to form a new loop selectively in either direction through a previously formed stitch while this is held open around one of said members, means for so operating said looping means in conjunction with different members of said series to form loops through stitches thereabout in succession, means operative to release the stitch from the member after the new loop has been formed therethrough, means for holding back the old stitch on the next member to be operative for knitting while the previous old stitch is being cast off, and means operative to cause the transfer of the new loops from the looping means to members of said series as new stitches in turn to be held open for further new loops to be formed through them by the looping means.

35. A knitting machine comprising looping means and a series of stitch-holding members, said looping means being constructed and arranged to form a new loop selectively in either direction through a previously formed stitch while this is held open around one of said members, means for operating said looping means in conjunction with different members of said series to form loops through stitches thereabout in succession, means operative to release the stitch from the member after the new loop has been formed therethrough, means for accepting the new loop and means for holding back the previously formed new loop while the new loop is being brought to accepted position, and means operative to enable the new loops formed by the looping means in their turn as new stitches to be held open and new loops formed through them by the looping means.

36. A knitting machine according to claim 31, having means for rocking the holding and accepting members out of and into the stitches.

37. A knitting machine according to claim 31, having means for sliding the holding and accepting members out of this and into the stitches.

38. A knitting machine according to claim 1, having an oscillatable looper and means for oscillating said looper first to penetrate the old stitch to engage the thread and draw a new loop and again to detach itself from the new loop.

39. A knitting machine comprising a looping means and a series of stitch holding members, said looping means being adapted to form a new loop selectively in either direction through a previously formed stitch while this is around one of said members, patterning means operative automatically to determine the direction in which the new loop is formed through said previously formed stitch means causing the looping means so to co-operate with different members of said series in succession, means operative to cause the transfer of the new loops from the looping means to members of said series as new stitches in turn to be held open for further new loops to be formed through them by the looping means, and means operative to cause the release of the previously formed stitches from the members.

40. A knitting machine comprising a looping means and a series of stitch holding members,

said looping means being constructed and arranged to engage the thread and form a new loop selectively in either direction through a previously formed stitch while this is held open around one of said members, means for relatively displacing said looping means and said members so that said looping means successively so co-operates with said members, means operative to cause the transfer of the new loops from the looping means to members of said series as new stitches in turn to be held open for further new loops to be formed through them by the looping means, means operative automatically to reverse the direction of such relative displacement to cause the looping means to form the further new loops in a reverse direction of the flow of the knitting, and means operative to cause the release of the previously formed stitches from the members.

41. A knitting machine comprising a looping means and a series of stitch holding members, means including a cam for causing said looping means to form a loop in one direction through a stitch while this is held open around one of said members and means including a cam for causing said looping means to form a loop in the other direction through a stitch while this is held open around one of said members, patterning mechanism for automatically selecting which one of said cams is operative so as to determine the direction in which the new loop shall be formed through the old stitch, and means for relatively displacing said looping means and said members so that said looping means co-operates with said members in succession, means operative to cause the transfer of the new loops from the looping means to members of said series as new stitches in turn to be held open for further new loops to be formed through them by the looping means, and means operative to cause the release of the previously formed stitches from the members.

42. A knitting machine according to claim 41, comprising mechanism including cams for reversing the direction of relative displacement of the looping means and said members and thereby the direction of flow of the knitting, and means for automatically selecting which of said cams shall be operative so that said looping means may form a loop selectively in either direction through a previously formed stitch in which-ever direction the knitting flow is progressing.

43. A knitting machine according to claim 29, in which said looper is displaceable bodily in one direction to form a new loop through a stitch holding member and transfer it to an accepting member and in the reverse direction for forming a new loop through a stitch about a holding member when knitting in the reverse direction, means including cams for effecting said displacements, and means operative automatically for placing one cam into operation and taking the other out of operation when the flow of knitting is to be reversed.

44. A knitting machine comprising a looping means and a series of stitch holding members, said looping means being constructed and arranged to engage the thread and form a new loop selectively in either direction through a previously formed stitch while this is held open around one of said members, means for displacing said members intermittently to knitting relation to said looping means so that the looping means co-operates successively with said members, means operative to cause the transfer of the new loops from the looping means to members of said series as new stitches in turn to be held open for further

new loops to be formed through them by the looping means, and means operative to cause the release of the previously formed stitches from the members, means for intermittently displacing said members in the reverse direction for reversing the flow of knitting, and means automatically controlling said reversal of displacement of said members.

45. A knitting machine comprising a thread laying means, a looper co-operating therewith, and a series of members, constructed to hold open stitches thereabout said looper co-operating with said thread laying means to engage the thread and form a new loop selectively in either direction through a previously formed stitch while this is held open around one of said members, and means for relatively displacing said thread laying means and looper and said members so that said looper so co-operates with members of said series holding stitches in succession, means operative to cause the transfer of the new loops from the looper to members of said series as new stitches in turn to be held open for further new loops to be formed through them by the looping means, and means operative to cause the release of the previously formed stitches from the members.

46. A knitting machine comprising a looping means, a series of stitch-guard members and a series of loop accepting members, means for operating said looping means to enable the latter to engage the thread and form a new loop through a previously formed stitch while this is held open around one of said guard members, and means for intermittently displacing said looping means so that it co-operates with first one guard member and one accepting member and then successively with other pairs of guard and accepting members.

47. A knitting machine comprising looping means, and stitch-holding means, said looping means being constructed and arranged to engage the thread and form a loop through a previously formed stitch while this is held open around said stitch holding means, and means to displace said stitch holding means while the new loop is held by the looping means so as to elongate said loop, and accepting means to accept said elongated loop.

48. A knitting machine comprising a stitch holding means having a channel adapted to hold open a stitch therearound with the return fold of the loop bridging the open top of the channel, and a looping means constructed and arranged to form a loop through said open stitch.

49. A knitting machine comprising looping means and a multiplicity of guard and accepting members and means for moving them progressively towards the looping means, so that some of the members acting as stitch guard members come successively with a previously formed stitch towards said looping means, and other of the members advance successively to receive a new loop, means for progressively moving said guard members towards the accepting members to relate the stitch thereabout to the looping means for knitting, and said looping means being constructed and arranged to engage the thread and form a new loop through said stitch, and means for advancing said accepting members successively toward the guard members to enable said accepting members successively to accept new loops, and means for progressively moving said accepting members away from the guard members after they have accepted new loops.

50. A knitting machine comprising looping means and a multiplicity of guard and accepting members and means for moving them progressively towards the looping means, so that the guard members come successively with a previously formed stitch towards said looping means, and the accepting members advance progressively to receive a new loop, means for progressively moving said guard members towards the accepting members to relate the stitch thereabout to the looping means for knitting, and said looping means being constructed and arranged to engage the thread and form a new loop through said stitch, and means for advancing said accepting members successively toward the guard members to enable said accepting members successively to accept a new loop, and means for progressively moving said accepting members away from the guard members after they have accepted new loops.

51. A knitting machine according to claim 46, in which means are provided to rock said stitch holding means away from the looping means to elongate the new loop.

52. A knitting machine according to claim 3, having means for successively sliding said stitch holding members in a direction transverse to the direction of relative displacement between such members and the looping means for withdrawing the member from the stitch after a new loop has been formed therethrough.

53. A knitting machine according to claim 7, having means for successively sliding said accepting members in a direction transverse to the direction of relative displacement between such members and the looping means for entering them into the new loops.

54. A knitting machine according to claim 1, in which the stitch-guard members have stitch holding channels or slots which open upwards and said looping means is oscillatable about a fixed axis thereabove, and means for oscillating said looping means about such axis for forming the new loops.

55. A knitting machine according to claim 5, comprising loop accepting members which have a chisel shaped edge chamfered to a point, and means for displacing said members so that said points move in close juxtaposition to the looping means supporting the loop when accepting the new loop.

56. A knitting machine according to claim 5, comprising a loop accepting members which have a chisel shaped edge chamfered to a point, and means for displacing said members to carry said point through the new loop in close juxtaposition to said looping means, said accepting members tapering from the widest part of the chisel end so that the new loop catches behind said widest part, and means for retracting the accepting member with the new loop so caught.

57. A knitting machine according to claim 6, comprising means to retract the stitch guarding member out of the old stitch after a new loop has been formed therethrough, and means for holding back the said stitch whilst the guarding member is withdrawing from it.

58. A knitting machine according to claim 6, in combination with a series of accepting members, and means for successively moving said members towards the looping means to accept new loops, and then away from the looping means with the new loop and means co-acting with said members to hold the new loop on the accepting member while this is receding.

59. A knitting machine according to claim 15, in which each system comprises spaced chain conveyors, said conveyors having transverse guides along which the guard and accepting members are displaceable transverse to the direction of motion of the conveyors, and means for successively displacing said members along said guides to relate them to the looping means.

60. A knitting machine according to claim 15, in which each system comprises spaced chain conveyors, said conveyors having transverse guides along which the guard and accepting members are displaceable transverse to the direction of motion of the conveyors, and means for displacing said members along said guides to relate them to the looping means, said guides being separate pieces, and said chain conveyors having fingers projecting from the chain links and by which said separate pieces are anchored.

61. A knitting means according to claim 15, having means for intermittently displacing said series in opposite directions.

HERBERT NOEL SMITH.
